US00D931273S

(12) **United States Design Patent** (10) **Patent No.:** **US D931,273 S**
(45) **Date of Patent:** **** Sep. 21, 2021**

(54) **LAPTOP COMPUTER**

(71) Applicant: **Quanta Computer Inc.**, Taoyuan (TW)

CN 303841245 * 9/2016
CN 305523256 * 12/2019

(72) Inventors: **Jui-Lung Wang**, Taoyuan (TW);
Chang-Ta Miao, Taoyuan (TW);
Chu-Fu Wang, Taoyuan (TW);
Gwo-Chyuan Chen, Taoyuan (TW)

(73) Assignee: **QUANTA COMPUTER INC.**,
Taoyuan (TW)

(**) Term: **15 Years**

(21) Appl. No.: **29/687,644**

(22) Filed: **Apr. 15, 2019**

(30) **Foreign Application Priority Data**

Jan. 8, 2019 (TW) 108300127

(51) LOC (13) Cl. **14-02**

(52) U.S. Cl.

USPC **D14/315**

CLAIM

The ornamental design for a laptop computer, as shown and described.

DESCRIPTION

FIG. 1 is a front perspective view of a laptop computer, showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front perspective view showing the laptop computer in a folded state; and,

FIG. 9 is an enlarged partial view of the area designated by the dashed circle and reference number 9 in FIG. 1. In FIGS. 1 and 9, the dashed lines represent the bounds of the claim and form no part thereof.

1 Claim, 9 Drawing Sheets
